UNITED STATES PATENT OFFICE

EMIL L. SCHNEPF, OF TRENTON, NEW JERSEY, ASSIGNOR TO SCAMMELL CHINA
COMPANY, OF TRENTON, NEW JERSEY

DESIGN FOR A PLATE

Application filed February 21, 1933. Serial No. 47,283. Term of patent 7 years.

To all whom it may concern:

Be it known that I, EMIL L. SCHNEPF, a citizen of the United States, residing at Trenton, in the county of Mercer and State of New Jersey, have invented a new, original, and ornamental Design for a Plate, of which the following is a specification, reference being had to the accompanying drawing, forming a part thereof.

Figure 1 is a plan view of the plate showing my new design, and

Figure 2 is a sectional view of the plate shown in Figure 1.

I claim:

The ornamental design for a plate, as shown.

EMIL L. SCHNEPF.
